INVENTOR

Fred L. Mackenzie
By his Attorney,
Nelson Howard

UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR PULLING FASTENINGS.

Application filed November 12, 1921. Serial No. 514,599.

This invention relates to the manufacture of shoes and is illustrated as embodied in a machine for pulling fastenings such as tacks which have been utilized as temporary means 5 for securing together shoe parts during the manufacture of shoes.

In manufacturing certain types of shoes, for example Goodyear welts, it is usual to secure each lasted upper to its insole and last by 10 means of tacks which form no permanent part of the completed shoe and which later, usually after the permanent fastening means have been inserted, must be removed. To facilitate the pulling of these lasting tacks it is usual 15 to drive them only part way so that their heads may be easily engaged by a tack pulling tool or machine. There are a number of different tack pulling machines in use at the present time which operate in an efficient manner. Most of these machines, however, have 20 a tendency to scatter the pulled tacks instead of delivering them to a receptacle such as is generally provided for that purpose. It is, accordingly, an object of the present invention 25 to provide a machine which, while no less effective in the tack pulling operation than the best of existing machines, will practically eliminate the scattering of pulled tacks.

With this object in view a feature of the invention 30 comprises the combination with tack pulling means of novel means, illustrated as a suction conduit or pneumatic conveyor, for carrying off the tacks as they are pulled. Preferably the intake of this conveyor or conduit is located adjacent to the point at which the tacks are released by the pulling means.

It occasionally happens that the head of a lasting tack is pulled off without the removal 40 of the shank of the tack from the lasted shoe. Moreover there are some operations in the manufacture of shoes, such as the tacking of a shank piece to a last upon which a turn shoe is to be relasted, in which headless fastenings are used which must later be extracted. With these circumstances in view it 45 is an object of the present invention to provide a machine which will be effective to pull headless fastenings. In the illustrative machine this is accomplished by causing the tack pulling jaws to bend the upper end of the fastening when they first engage it so as to form in effect a head by means of which it is pulled during the continued operation of the pulling jaws.

With the above and other objects and fea-

tures in view the invention will now be described in connection with the illustrative machine of the accompanying drawings and pointed out in the claims.

In the drawings,

Fig. 1 is a side elevation of a tack pulling machine embodying the present invention;

Fig. 2 is a side elevation on a larger scale of the head of the machine;

Figs. 3, 4 and 5 are detail views of the tack pulling jaws and associated parts showing them in different positions which they successively assume during the pulling of headed fastenings;

Fig. 6 illustrates the use of the tack pulling jaws to extract a headless fastening; and

Figs. 7 and 8 illustrate diagrammatically the paths of movement of the pulling jaws when adjusted to extract headed and headless fastenings respectively.

The illustrated machine is provided with a column 8 carrying a head 10 upon which are mounted tack pulling instrumentalities 12 having adjacent thereto the intake opening 14 of a pneumatic conveyor comprising a conduit 16 provided with a power operated pump or fan 18 arranged to cause suction through the conduit. Mounted in the head of the machine is a shaft 20 driven from any source of power and provided with an eccentric 22 and 25 a cam member or members having cam tracks 24 and 26. Journaled in bearings in the head of the machine is a rock shaft 28 carrying a lever 30 one end of which is pivoted to the rod of an eccentric strap 32 co-operating with eccentric 22 to oscillate lever 30 as shaft 20 rotates. Pivoted to the other extremity of lever 30 are a pair of levers 34 and 36 carrying cam rolls operating in cam tracks 24 and 26 respectively. At their extremities opposite the cam rolls levers 34 and 36 support a pair of tack pulling jaws 38 and 40. The formation of cam tracks 24 and 26 and their relation to eccentric 22 is such that jaws 38 and 40 are moved towards one another when at the lower extremities of their paths of movement, as diagrammatically illustrated in Fig. 7, and are thus caused to grip the tacks beneath their heads and to maintain this grip as they move upwardly to extract the tacks. When the tacks are opposite the intake opening 14 the jaws 38, 40 move apart and release the tacks which are then sucked through the opening 14 into the conduit and carried off to a suitable receptacle which may be provided for

100
105
110

that purpose. To prevent the pulled tacks from passing beyond the opening 14 a deflector 42, Fig. 1, is provided adjacent to the opening and transverse of the path of pulling movement of jaws 38 and 40.

Jaws 38 and 40 are mounted by means of screw and slot connections 44 and 46 so as to be capable of vertical adjustment. Jaw 40, moreover, is mounted by means of a similar screw and slot connection 48 for horizontal adjustment towards and from jaw 38. It will thus be apparent that by raising jaw 40 with respect to the jaw 38 and by adjusting it so that its path of movement towards the tack 15 will overlap that of jaw 38, as indicated in Fig. 8, the two jaws may be caused to engage headless fastenings upon opposite sides at different points along their lengths so that the fastenings will be bent as indicated in Fig. 20 6 in a manner which will overcome the tendency of the jaws to slide off the ends of the fastenings and will in effect result in the formation by the machine of heads upon these headless fastenings prior to the pulling 25 thereof.

As illustrated the tack pulling jaws are provided with a pair of guards 50, 52 arranged to prevent the work from being moved into such position as to be pinched between the jaws or 30 in any way damaged thereby.

Having described my invention, what I claim as new and desire to secure by Letters Patent of the United States is:

1. A machine of the class described having, 35 in combination, movable fastening pulling means, and independent means acting upon the fastenings at the point at which they are pulled for carrying off said fastenings from the pulling means.

40 2. A machine of the class described having, in combination, fastening pulling means, and means arranged independently of the fastening pulling means to carry off fastenings from the point at which they are pulled.

45 3. A machine of the class described having, in combination, fastening pulling means, and a pneumatic conveyor arranged to carry off pulley fastenings.

4. A machine of the class described having, 50 in combination, fastening pulling means, a part adjacent to the point at which said fastenings are pulled, said part having an opening therein, and a power-operated conveyor arranged to carry off pulled fastenings which 55 have been received by said opening.

5. A machine of the class described having in combination, fastening pulling means, a part adjacent to said means having an opening therein, and a suction device for causing 60 pulled fastenings to be carried off through said opening.

6. A machine of the class described having, 65 in combination, fastening pulling means, a part adjacent to said means having an opening therein, and a pneumatic conveyor ar-

ranged to carry off pulled fastenings through said opening.

7. A fastening pulling machine having, in combination, a conduit having an intake opening, fastening pulling means arranged 70 to release pulled fastenings adjacent to said opening, and means for carrying the released fastenings through the opening.

8. A machine of the class described having, 75 in combination, fastening pulling means, a conduit having an opening adjacent to said means, and means for producing an air current in said conduit to carry off pulled fastenings.

9. A machine of the class described having, 80 in combination, fastening pulling means, a conduit having an opening adjacent to said means, and a pump arranged to produce an air current through said conduit to carry off pulled fastenings 85

10. A machine of the class described having, 90 in combination, fastening pulling means, a conduit having an opening adjacent to said means, and a fan arranged to cause an air current in said conduit to carry pulled fastenings through the opening and into and through the conduit.

11. A tack pulling machine having, in combination, a pair of tack pulling jaws, a conduit, and means for causing suction in the 95 conduit, the conduit having an intake opening adjacent to the jaws arranged to receive the tacks from the jaws.

12. A fastening pulling machine having, in combination, fastening pulling means, a part 100 having an opening adjacent to said means, a deflector adjacent to the opening to prevent the passage of pulled fastenings therewith, and power-operated means for carrying off the pulled fastenings. 105

13. A fastening pulling machine having, in combination, fastening pulling means, a conduit having an opening adjacent to said means, a suction device for causing an air current in the conduit to suck pulled fastenings 110 therethrough, and a deflector adjacent to the opening to prevent the passage of the pulled fastenings therewith.

14. A machine of the class described having, in combination, fastening pulling means, 115 a conduit having an opening adjacent to said means, a deflector arranged to prevent the passage of fastenings past said opening, and a fan arranged to produce an air current in said conduit to carry the pulled fastenings 120 through the opening and into and through the conduit.

15. A fastening pulling machine having, in combination, a fastening pulling jaw, a conduit opening adjacent to said jaw, and a 125 conveyor for carrying off pulled fastenings through said opening.

16. A fastening pulling machine having, in combination, a pair of fastening pulling jaws, a part having an opening adjacent to 130

said jaws, and a suction device for carrying off pulled fastenings through said opening.

17. A fastening pulling machine having, in combination, a conduit having an intake opening, a pair of fastening pulling jaws arranged to release the pulled fastenings adjacent to said opening, and means for carrying the released fastenings through the opening.

18. A fastening pulling machine having, in combination, a pair of fastening pulling jaws, a conduit having an intake opening adjacent thereto, and a fan arranged to suck pulled fastenings through the opening.

19. A fastening pulling machine having, in combination, a pair of fastening engaging and pulling jaws, and means for actuating said jaws to cause them to approach and grip fastenings and then together to be retracted from the work, said means being operable to cause the jaws to bend the fastenings upon their engagement therewith.

20. A fastening pulling machine having, in combination, a pair of fastening pulling jaws, and means for actuating said jaws to cause them to approach and grip a fastening unsymmetrically to cause the fastening to bend as the jaws close thereon.

21. A fastening pulling machine having, in combination, a pair of fastening engaging and pulling jaws, and means for operating said jaws to cause them to grip and pull fastenings, one of the jaws being adjustably mounted so that the jaws may be arranged to grip the fastening either with the jaws in alinement or with the jaws relatively displaced so that they engage the fastening upon opposite sides at different points along its length.

22. A fastening pulling machine having, in combination, a pair of fastening pulling jaws, and means for actuating said jaws to cause them to approach and grip a fastening

with the fastening engaging portion of the two jaws out of alinement in the direction of the length of the fastening so as to bend the fastening as the jaws engage therewith.

23. A fastening pulling machine having, in combination, a pair of fastening engaging and pulling jaws, and means for actuating said jaws to cause them to grip and pull fastenings, the jaws being adjustably mounted so that they may be arranged to grip the fastenings either with the jaws in alinement or with the jaws relatively displaced so that they engage the fastenings upon opposite sides at different points along their length.

24. A fastening pulling machine having, in combination, a pair of fastening pulling jaws arranged to form a head upon a headless fastening and thereafter to pull the fastening.

25. A fastening pulling machine having, in combination, fastening pulling members, and means for operating said members to cause them to form a head upon a headless fastening and to pull the fastening.

26. A fastening pulling machine having, in combination, fastening pulling instrumentalities constructed and arranged to form a head upon a headless fastening and to extract the fastening by a pull exerted upon the head thus formed.

27. A fastening pulling machine having, in combination, a pneumatic conveyor, and fastening pulling means located adjacent to the conveyor and arranged to reciprocate between two extreme positions in one of which positions the fastening is pulled and in the other of which positions the fastening is discharged from the pulling means into the pneumatic conveyor.

In testimony whereof I have signed my name to this specification.

FRED L. MACKENZIE.
